UNITED STATES PATENT OFFICE.

JOHN C. BOWERS, OF NORWAY, MAINE.

COMBINATION TOOL.

Application filed April 5, 1923. Serial No. 629,975.

To all whom it may concern:

Be it known that I, JOHN C. BOWERS, a citizen of the United States, residing at Norway, Maine, have invented new and useful Improvements in Combination Tools, of which the following is a specification.

The present invention relates to improvements in combination tools, and has for its general object the provision of a unitary device which embodies a plurality of elements of a recognized utility.

More specifically the object of my invention is to provide a device of the aforesaid character which may be economically produced and is so designed as to permit of the employment of the various elements of which it is composed, for the specific purposes for which said elements are devised, with the greatest ease and facility. The several elements of the device are compactly assembled so that it may be carried in the pocket of the user without discomfort or without possibility of damage to the clothing.

My invention further contemplates an assemblage of a plurality of utilitarian elements in association with a supporting medium which may function as a handle or grip in the manipulation of the various elements and will provide a means for carrying keys or other implements which are customarily held on a suitable retainer, when carried in the pocket.

Other objects and advantages of my invention will become manifest as the description proceeds and I will have it understood that I reserve unto myself all rights to the full range of equivalents, both in structure and use, to which I may be entitled under my invention in its broadest aspect.

For the purposes of the present disclosure, I have elected to illustrate and describe the preferred embodiment of my invention, but it will be obvious that my invention may take other forms and that different utilitarian elements may be substituted for those shown without departing from the spirit and scope of my invention.

In the accompanying drawings:

Fig. 1 is a plan view, partly in section, of a combination tool or implement made in accordance with my invention, showing the relative positions of the several elements when the device is to be carried in the pocket and when the frame functions as a key-retaining medium;

Fig. 2 is a view similar to Fig. 1, showing the corkscrew element disposed at right angles to the supporting frame when it has been moved to the position shown in dotted lines in Fig. 3;

Fig. 3 illustrates the position assumed by the corkscrew element, when it is desired to disengage the same from the juxtaposed frame members in order that it and its supporting medium may be moved to the position shown in dotted lines;

Fig. 4 is a side elevation of my device, showing the corkscrew element disposed at right angles to the supporting frame when it has been moved to the position shown in dotted lines in Fig. 3;

Fig. 5 illustrates a method whereby keys or other objects may be placed upon, or removed from, the supporting frame when the corkscrew element is disengaged from the frame and removed to the position which it occupies in Fig. 4;

Fig. 6 is an enlarged detail of a portion of the supporting frame, as indicated at 6 in Fig. 1, illustrating the pivotal mounting of the pin which supports the corkscrew element; and

Fig. 7 is a transverse sectional view on the line 7-7 of Fig. 2.

Referring now to the drawings in detail, in which like characters of reference are employed to designate similar parts in the several views, 8 indicates the supporting frame, which may be of the general configuration of a triangle as shown; two of the sides thereof merging into the parallel extensions 9 and 10. This frame may be made of any suitable material. In the present embodiment of my invention I have utilized round stock for the formation of the frame which presents a more pleasing appearance and readily lends itself to attaining the objects of my invention.

It will be observed that the extension 10 of the frame 8 is slightly shorter than the extension 9 thereof and is provided with an offset member 11 extending upwardly from its lower end and shaped to form a device for effecting the removal of bottle caps or stoppers of the so-called "crown" type. This device 12 is of the conventional configuration of such implements and is employed in the usual manner as hereinafter will be apparent.

The base of the offset member 11 is slotted or bifurcated, as shown at 13 in Fig. 1, to form a bearing within which a transverse pin 14 is pivotally mounted as indi-

cated at 15. This pin 14, it will be noted, carries an element 16, which is freely rotatable thereon, the free end of said pin being threaded to receive a securing nut or 5 the like 17.

In the present embodiment of my invention the aforesaid element 16 comprises a corkscrew 18, nail file 19, finger-nail cleaner 20 of the usual configuration, and an implement corresponding to the usual so-called "strip" can-key opener, which is formed by the provision of a slot 21 between said finger-nail cleaner 20 and the cooperating extension 22, which terminates inwardly of the 10 15 finger-nail cleaner 20. The said extension 22 is preferably formed with a rounded or curved surface at its extremity, and by spacing it inwardly of the end of the finger-nail cleaner 20 serves to some extent as a guard 20 or stop to prevent the entrance of the relatively sharp end of the latter implement into the cloth of the pocket, when my device is thus carried.

The body portion 23 of the element 16 is 25 preferably of round stock and the opposed faces of the extensions 9 and 10 of the frame 8 are grooved or recessed to conform to the contour thereof, so that when said extensions are in engagement with said body 30 35 portion of the element 16 and locked in position by means of a nut or the like 17, the said element 16 will be rigidly held against movement with relation to the frame 8 and for all practical purposes will be, in effect, an integral part thereof.

As will be clearly apparent from Fig. 1 of the drawings, the end of the extension 9 of the frame 8 is formed with an open slot 24 within which the threaded end of the 40 transverse pin 14 is passed when the element 16 is supported within the frame of the device. Obviously, by unscrewing the nut 17, the pressure of the extensions 8 and 9 upon the body portion 23 of the element 16 will 45 be relieved and the said element may be rotated on the pin 14 until it assumes a position at right angles to the frame, as shown in Figs. 3 to 5 inclusive. When the element 16 has been rotated to this position, the pin 50 55 14 may be disengaged from the slot 24 and moved in an arc on its pivot 15 to the position shown in Fig. 5, that is, outwardly of the frame so that an unobstructed passage is provided between the frame extensions 9 and 10 to permit of the placing of keys or other objects on the said frame 8, as illustrated in Fig. 5.

In the normal employment of my device, the element 16 is locked in position within 60 the extensions of the frame, so that the point of the corkscrew 18 will abut against the head of the frame and will, thereby, be prevented from coming into accidental engagement with the fabric of the pocket, if the 65 device is being carried in that manner.

Furthermore, it is manifest that the element 16 divides the frame into halves and when keys are carried on the latter, those used for different purposes may be separated by said element. If it is desired to use the corkscrew 18 of the element 16, the nut 17 is 70 loosened sufficiently to permit said element 16 to rotate on the pin 14 in frictional engagement with the frame extensions 9 and 10 so as to bring the corkscrew into the position shown in Fig. 2, the frame 8 functioning as a "pull" or grip for said element. 75

The element 16 will preferably be retained in the position shown in Fig. 1 in those cases where it is desired to employ the nail file 19, the finger-nail cleaner 20, or the strip can opener 21, while the bottle-cap remover 12 may be manipulated without respect to the position of the element 16, the nib 12^a thereof cooperating with the contiguous portion 80 85 of the frame of the device in the functioning of the implement.

The securing nut 17 may be of any desired shape, but I have found it preferable to provide it with a convex surface 17^a at its inner 90 end for engagement with the extension 9 which, if desired, may be formed with a suitable seat to add to the security of the locking effect of said nut.

From the foregoing description of my invention it will be evident that I have devised a combination tool which possesses great utility and one in which the various elements may be brought into effective position, with relation to the supporting frame, with a 95 100 minimum of effort. Furthermore, it will be noted that I have made provision for adequately protecting the fabric of the pocket against injury by the pointed ends of the several implements, when the device is so 105 carried, in a manner which does not in any way detract from the effectiveness of the implements when in use.

What is claimed is:

1. A combination tool having a frame 110 formed with spaced terminals, an element rotatably supported from one of said terminals, means for locking said element in frictional engagement with both of said terminals to close the space therebetween, and means whereby the said element may be disengaged from said terminals and moved to a position with relation thereto to permit of mounting other objects on said frame by passing them over one of said terminals onto 115 the body of the frame.

2. A combination tool having a frame of the general configuration of a triangle, the converging sides thereof merging into parallel extensions, a pin pivotally connected to 125 one of said extensions, an element rotatably mounted on said pin, said pin being adapted to cooperate with the other extension whereby said element may be positioned between said extensions, and means associated with 130

said pin for locking said element in frictional engagement with said extensions.

3. A combination tool having a frame formed to provide two parallel members, a pin pivotally connected to one of said members, an element embodying a plurality of implements rotatably mounted on said pin, and means associated with said pin for locking said element in frictional engagement with said members.

4. A combination tool having a frame adapted for use as a key-ring or the like, said frame terminating in spaced extensions, a pin pivotally mounted on one of said ex-

tensions, an element embodying a plurality ¹⁵ of useful implements carried by said pin and adapted for disposition within the space between said extensions, and means cooperating with said pin and one of said extensions for locking said element in frictional engagement with both of said extensions, said element being capable of movement with relation to said frame to provide an unobstructed passage between said extensions whereby ²⁰ keys or the like may be mounted on said ²⁵ frame.

JOHN C. BOWERS.
